UNITED STATES PATENT OFFICE.

WALTER JESSE SPIRO, OF NEW YORK, N. Y., ASSIGNOR TO COLUMBIA TYPEWRITER MANUFACTURING COMPANY, OF NEW YORK, N. Y., A CORPORATION OF NEW YORK.

TABULATING ATTACHMENT.

SPECIFICATION forming part of Letters Patent No. 785,983, dated March 28, 1905.

Application filed April 25, 1904. Serial No. 204,918.

To all whom it may concern:

Be it known that I, WALTER JESSE SPIRO, a citizen of the United States, residing at New York, in the county of New York, State of New York, have invented certain new and useful Improvements in Tabulating Attachments, of which the following is a specification, reference being had therein to the accompanying drawings.

10 This invention relates to a tabulating attachment for type-writers, and particularly to a structure embodying a series of carriage-stops—such, for instance, as shown in the patent to Charles Spiro, No. 543,111, dated July 23, 1895—associated with a carriage-release device, whereby a simultaneous movement of both the stop and release mechanisms is obtained.

15 The invention has for an object to provide an improved construction and arrangement of the stop-keys relative to the release-key whereby these keys may be simultaneously depressed or operated to interpose a stop in the path of the stop-rack of the carriage and 20 to remove or release the regular feeding mechanism from the carriage.

25 A further object of the invention is to provide a construction and arrangement of the stop-levers and associated parts whereby they may be nested or disposed within a minimum space and properly arranged for independent operation from a keyboard.

30 Another object of the invention is to provide means upon the stop-keys for permitting a movement of said keys after the stop is thrown in position and for the purpose of effecting the release of the feed mechanism from the carriage through a separate device operable simultaneously with the stop-keys.

35 Another object of the invention is to provide an improved construction and arrangement of connecting keys and levers for the purpose of releasing the ordinary feed mechanism of a type-writer by jointly removing the 40 dogs from the star-wheel with which they ordinarily operate.

45 Other and further objects and advantages of the invention will be hereinafter set forth,

and the novel features thereof defined by the appended claims.

50 In the drawings, Figure 1 is a plan of a portion of a type-writer, showing the attachment applied thereto with parts broken away and in section; Fig. 2, a side elevation with the end wall of the casing for the attachment removed; Fig. 3, a rear elevation of the casing for the attachment removed and parts in section; Fig. 4, a diagrammatic perspective of one of the stop connections in its associated relation with the release connections; Fig. 5, a 55 similar view showing the stop-rack carried by a carriage in connection with the independent operable stops; Fig. 6, a top plan view of the escapement mechanism shown in Fig. 4, and Fig. 7 a detail perspective of one of the stop-keys.

60 Like letters of reference refer to like parts in the several figures of the drawings.

65 This invention is applicable to any form or ordinary construction of type-writer, but for the purpose of illustration is here shown in connection with the type of machine known as a "bar-lock" and comprising generally a frame A, having a type-bar segment A¹ and a platen-carriage A² mounted thereon, said carriage being provided with a feed-rack A³, cooperating with the usual escapement mechanism, as shown in Figs. 4 and 6. At one side of the platen a ribbon-carrier A⁴ is disposed, and at the front of the machine the usual 70 space-bar A⁵ is connected by the keys A⁶ to oscillate the feed mechanism. The carriage is also provided at the rear with a stop-rack A⁷ of usual construction and provided with stops A⁸, pivotally mounted upon a longitudinal rod A⁹, so as to be rotatable out of engagement with the teeth of the rack A⁷, said stops being provided with a recessed portion A¹⁰ to engage said rack and with a contacting face A¹¹ below the rack to engage with the independent stops B when the same are thrown into the path of the stops upon the rack. These parts are of the usual construction, and the invention is not confined to the use thereof, as other arrangements may be 75 provided to perform a similar function.

The tabulating attachment herein disclosed may be disposed in any desired position and is here shown as contained within an angularly-formed casing attached to one side and back of a type-writer, said casing comprising an end wall C and a back wall C', while opposite the end wall C at the back of the casing a support C² is provided and adapted to receive a pivoting-rod C³, upon which each of the levers B', carrying the separate stops B, are mounted at opposite ends. These levers are substantially U-shaped in form, and the end portions thereof are disposed at an angle to the body and are of less length than said body, thus providing a pivotal mounting at each end thereof, one end, B², having a stop B secured thereon, while the opposite end, B³, is connected with a stop-key B⁴ by means of a ligament B⁵, as shown in Fig. 4, while this key is pivotally mounted upon the cross-pin B⁶, carried by the case of the attachment, and the outer free end of the key provided with a finger-post B⁷, pivoted thereon and at an angle thereto. As shown in Fig. 7, the key B⁴ is provided at its pivotal point with a slotted aperture B⁸ and is normally held in a raised position by means of a tension-spring B⁹, extending therefrom to a fixed part. This slotted aperture permits a continued movement of the key after the stop controlled thereby has been thrown in position, which is necessary in order that a movement of the simultaneously-operated escapement-key may be continued after the completion of the stop movement. This escapement-operating mechanism may be constructed and arranged in any desired manner to operate simultaneously with any one of the stops and be yet capable of movement separately therefrom; but as showing a desirable form of this construction a plate D is provided at the keyboard of the attachment and formed with apertures D', through which the posts B⁷ of the stop-keys extend. This plate is pivotally mounted upon a fixed frame of the attachment, as shown at D², and is connected with a release-key D³ by means of a pivotal connection D⁴, as shown in Fig. 4, the inner end of this key being connected by a ligament D⁵ with the angularly-disposed end D⁶ of the rock-lever D⁷, which is pivotally mounted upon the rod C³ by means of the portion D⁶ and a similar portion D⁸ at the opposite end of the lever. The downward movement of this lever contacts with the U-shaped end E of the escapement-lever E', which is so shaped in order to permit a proper disposition within the back of a type-writer casing and also the pivotal mounting of the lever upon the back of the casing at E², at which point it is also provided with a restoring-spring E³. The opposite end of this lever is extended at a right angle thereto, as shown at E⁴, and there provided with a curved striker-face E⁵, adapted to engage an angular lip E⁶, depending from the pivotally-mounted yoke

E⁷, carried at the opposite ends of the escapement mechanism and there provided with fingers E⁸, one of which is adapted to engage and depress the dogs F by means of a tail F' from the main pivot-dog disposed beneath the finger, 70 while the other finger may be operated by a carriage-release bail. The main dog F² is pivoted at its lower portion to rock away from the star-wheel F³, with which the dogs ordinarily engage to release the escapement, and 75 at its pivotal point is carried by the usual rocking support F⁴, connected with the space-bar by means of the keys A⁶ and the usual connections. Upon the main dog F² the secondary dog F⁵ is pivotally mounted at F⁶, so 80 as to be carried away from the star in the movement of the primary dog. The star or spur wheel F³ is provided upon its shaft with a pinion F⁷, adapted to engage the feed-rack A³ of the carriage. The plate D, which controls the release-key, may be provided with any desired marking or characters to indicate the denomination or degree of space formed by the separate stops controlled by the stop-keys disposed within the area of said plate, 85 these parts being so arranged that the depression of the stop-key carries with it the plate, thus primarily drawing the stop into the path of the stop-rack on the carriage, while the slotted pivoting-aperture of the stop-key permits it to continue its movement downward after the stop is thrown in position, in order that the plate may fully accomplish the release of the ordinary escapement mechanism. 90

In the operation of the invention it will be 100 seen that the depression of the pivoted plate D carries downward the outward end of the release-key D³, which is mounted on the pivot B⁶ and normally held in raised position by means of one or more springs D⁹, extending 105 to a fixed part. The inner end of the release-key is connected with the rocking lever D⁷ by means of the ligament D⁵, extending from the key to the angular end D⁶ of the lever. The body of this lever in its downward 110 movement is adapted to strike the angularly-disposed end E of the lever E', pivoted upon the back of the machine-frame at E². This lever normally lies beneath the plane of the type-keys, and the arm E⁴ thereof is extended 115 upward therefrom between adjacent keys and provided with the striker-face E⁵, adapted to engage the angular lip E⁶, depending from the release-lever E⁷, pivotally mounted upon the frame of the escapement mechanism and having at one side of its pivot the dog-finger E⁸, adapted to engage the tail F' of the primary dog F². This dog is pivoted upon the rocking plate F⁴ of the escapement, and has pivotally mounted thereon a co-operating dog F⁵, 120 these dogs jointly operating in connection with the star or spur wheel F³ in the usual well-known manner. The rocking plate F⁴ is adapted to be operated in the usual manner 125 from the space-key of the machine to perform 130

the step-by-step feeding function, while the engagement of the dog-finger of the release-lever with the dogs oscillates them out of engagement with the star-wheel, thus leaving 5 the carriage free for movement under the usual spring tension, and this action can be accomplished by the depression of the plate D and release-key without throwing any of the stops into position. It is, however, desirable 10 in tabulated or denominational work to throw a stop into engagement with the stop-rack A⁷, carried by the carriage, and this is accomplished by the engagement of the finger of the operator with both the post B⁷ of the stop-key and the plate D of the release-key, thus effecting 15 a simultaneous movement of these two parts to first throw a stop into the path of its rack and then release the escapement mechanism. The pivotal opening in this stop-key is, as before stated, elongated, so as to permit 20 a continued downward movement of the key simultaneous with the movement of the release-key after the stop has been thrown in position and its further travel stopped by contact with the casing above the stop-lever, while at other times the tension of the spring 25 is sufficient to hold the lower portion of this slot in engagement with the pivot, so that it acts upon this point as a pivotal center. The 30 series of stop-keys are independently and separately connected with the several stop-levers B', which carry a stop B in a different relative position to the rack upon the carriage and adapted to engage the stop finger or block 35 carried by this rack to effect a stoppage of the carriage at the desired point. These stop-levers are nested one within the other, as shown in Fig. 1, so as to occupy a minimum space and to provide for a pivoting of all of 40 the same upon a common pivot and in the same horizontal plane, which is desirable in connection with the structure of machine here shown.

It will be obvious that changes may be made 45 in the details of construction and configuration without departing from the spirit of the invention, such changes being within the ordinary skill of a mechanic familiar with the art to which this invention relates.

Having described my invention and set forth 50 its merits, what I claim, and desire to secure by Letters Patent, is—

1. In a tabulating mechanism, means for operating denomination-stops, separate means 55 for releasing an escapement mechanism independently of any denomination-stop and arranged for simultaneous operation with any one of the denomination-stop-operating mechanisms to release the escapement and means for 60 permitting a continued movement of the stop-operating means subsequently to the completion of the travel of a denomination-stop.

2. In a tabulating mechanism, means for operating denomination-stops, separate means

for releasing an escapement mechanism arranged 65 for simultaneous operation with any one of the denomination-stop-operating mechanisms to release the escapement, and means for permitting a continued movement of the stop-operating means subsequently to the completion 70 of the travel of a denomination-stop.

3. In a tabulating attachment, a stop mechanism, pivoted keys for operating the stops thereof, an escapement-releasing key independent of any stop of said mechanism and 75 disposed adjacent to the stop-key for joint movement therewith, and means to permit a continued pivotal movement of the stop-key with the release-key after the stop has reached the limit of its travel into operative position. 80

4. In a tabulating attachment, a stop mechanism comprising a series of stops and keys extending therefrom, an escapement-releasing mechanism, a key extending therefrom, a pressure-plate carried by said key, finger-pieces 85 from each of the stop-keys extending through said plate, and means to permit a continued travel of the stop-keys with the release-key after the stop has reached the limit of its travel into operative position. 90

5. In a tabulating attachment, a stop mechanism comprising a series of stops and keys extending therefrom, an escapement-releasing mechanism, a key extending therefrom, a pressure-plate carried by said key, finger-pieces 95 from each of the stop-keys extending through said plate, a common pivot for said stop-keys extending through a vertically-disposed slot therein, and independent springs for supporting each of said stop-keys in a 100 raised position.

6. In a tabulating attachment, a stop mechanism comprising a series of stops and keys extending therefrom, an escapement-releasing mechanism, a key extending therefrom, a pressure-plate carried by said key, finger-pieces 105 from each of the stop-keys extending through a vertically-disposed slot therein, independent springs for supporting each of said stop-keys in a raised position, angular levers 110 carrying said stops at one end and pivotally mounted at the opposite end, and connecting-links extending from the stop-keys to said levers.

7. In a tabulating mechanism, a stop-operating key, means for permitting a continued movement of the stop-key after the stop has reached the limit of its travel into operative position, and a separate releasing-key constructed and arranged for travel either independently 120 of the stop-key to release a carriage or for simultaneous movement with the stop-key to set a stop and, subsequently, release a carriage. 115

8. In a tabulating mechanism, a stop-operating key, a separate releasing-key constructed and arranged for simultaneous movement with the stop-key, and means for permitting a con- 125

tinued movement of the stop-key with the release-key after the stop has reached the limit of its travel into operative position.

9. In a tabulating mechanism, a series of 5 stop-keys, a releasing-key constructed and arranged to travel independently of the stop-keys to release a carriage or be operated simultaneously with any one of said stop-keys to set a stop and subsequently release a carriage, 10 and means for permitting a continued movement of the stop-keys with the release-key after the stop has reached the limit of its travel into operative position.

10. In a tabulating mechanism, a series of 15 stop-keys, an independent release-key constructed and arranged to be operated independently of any stop or simultaneously with any one of said stop-keys to release the escapement mechanism after the stop has reached 20 the limit of its travel into operative position, and means for permitting a continued movement of a member of the stop-keys simultaneously with the release-key after the stop has reached the limit of its travel into operative position.

11. In a tabulating mechanism, a rock-lever having opposite angularly-disposed end portions, a supporting-pivot extending through said end portions, a stop carried by one of 30 said end portions, and means connected to the opposite end portion to oscillate the lever.

12. In a tabulating mechanism, a series of rock-levers having angularly-disposed end portions, means for pivotally supporting said 35 end portions, a stop carried by one of said end portions, and means connected to the opposite end portions to oscillate the levers, said levers being nested one within the other.

13. In a tabulating mechanism, a series of 40 rock-levers having angularly-disposed end portions, a stop carried by one of said end portions, means connected to the opposite end portions to oscillate the levers, said levers being nested one within the other, and a common pivot for the end portions of all of said levers.

14. In a tabulating mechanism, a series of substantially U-shaped rock-levers nested together and provided at one end with independent stops, and means for oscillating said levers.

15. In a tabulating mechanism, a series of substantially U-shaped rock-levers nested together and provided at one end with independent stops, pivoted operating-keys for said levers disposed in a different plane therefrom, and ligaments pivotally connecting said keys and levers.

16. In a tabulating mechanism, a series of substantially U-shaped rock-levers nested together and provided at one end with independent stops, pivoted operating-keys for said levers disposed in a different plane therefrom, ligaments pivotally connecting said keys and levers, a release-key, a rock-lever parallel

with the stop-levers and connected with said 65 key, and means adapted to be engaged by the stop rock-lever to release the escapement mechanism.

17. In a tabulating mechanism, a series of substantially U-shaped rock-levers nested together and provided at one end with independent stops, pivoted operating-keys for said levers disposed in a different plane therefrom, ligaments pivotally connecting said keys and levers, a release-key, a rock-lever parallel 75 with the stop-levers and connected with said key, a release-lever pivotally mounted between its ends and having at one end an arm to engage the release rock-lever and at the other end an arm to engage the dog-releasing 80 mechanism.

18. In a tabulating mechanism, a series of substantially U-shaped rock-levers nested together and provided at one end with independent stops, pivoted operating-keys for said levers disposed in a different plane therefrom, ligaments pivotally connecting said keys and levers, a release-key, a rock-lever parallel 85 with the stop-levers and connected with said key, a release-lever pivotally mounted between its ends and having at one end an arm to engage the release rock-lever and at the other end an arm to engage the dog-releasing mechanism, a pivoted dog mechanism, and a dog-releasing lever provided with an angular 95 lip adapted to engage the arm from the release-lever, and a finger to engage the tail from the dog.

19. In a tabulating mechanism, a series of pivoted stop-keys and stops controlled thereby, a pivoted releasing-key, a plate connected with said releasing-key and provided with a series of apertures to receive the posts from the stop-keys, and means for normally retaining the posts and plate in a raised position.

20. In a tabulating mechanism, a series of pivoted stop-keys and stops controlled thereby, a pivoted releasing-key, a plate connected with said releasing-key and provided with a series of apertures to receive the posts from the stop-keys, means for normally retaining the posts and plate in a raised position, and a series of rock-levers carrying at one end a stop and connected at their opposite ends with the stop-keys, said stops being disposed in parallel planes.

21. In a tabulating mechanism, a series of pivoted stop-keys and stops controlled thereby, a pivoted releasing-key, a plate connected with said releasing-key and provided with a series of apertures to receive the posts from the stop-keys, means for normally retaining the posts and plate in a raised position, a series of rock-levers carrying at one end a stop and connected at their opposite ends with the stop-keys, said stops being disposed in parallel planes, a rock-lever connected to the release-key, and means disposed beneath said re-

lease rock-lever to control the escapement mechanism.

22. In a tabulating mechanism, a release-key, a release-lever adapted to be operated therefrom, a yoke-arm disposed at an angle to one end of said lever to receive motion from said key, and an arm extending from the opposite end of said lever to control an escapement mechanism.
23. In a tabulating mechanism, a release-key, a release-lever adapted to be operated therefrom, a yoke-arm disposed at an angle to one end of said lever to receive motion from said key, an arm extending from the opposite end of said lever to control an escapement mechanism, a pivot for said lever between the opposite ends, and a restoring-spring encircling said pivot and engaging the under face of said lever at opposite sides of the pivot.
24. In a tabulating mechanism, a release-key, a release-lever adapted to be operated therefrom, a yoke-arm disposed at an angle to one end of said lever to receive motion from said key, an arm extending from the opposite end of said lever to control an escapement mechanism, a pivot for said lever between the opposite ends, a restoring-spring encircling said pivot and engaging the under face of said lever at opposite sides of the pivot, a pivoted dog-lever having an angular lip depending therefrom to be engaged by the end of the release-lever, and a dog-finger disposed at the opposite side of the pivots of the dog-lever from said lip.
25. In a tabulating mechanism, a release-key, a release-lever adapted to be operated therefrom, a yoke-arm disposed at an angle to one end of said lever to receive motion from said key, an arm extending from the opposite end of said lever to control an escapement mechanism, a pivot for said lever between the opposite ends, a restoring-spring encircling said pivot and engaging the under face of said lever at opposite sides of the pivot, a pivoted dog-lever having an angular lip depending therefrom to be engaged by the end of the release-lever, a dog-finger disposed at the opposite side of the pivots of the dog-lever from said lip, a pivoted primary dog having a tail to be engaged by said dog-finger, and a sec-

ondary dog pivotally mounted upon the primary dog to travel in the movement thereof.

26. In a tabulating mechanism, means for operating column-stops, means independent of a column-stop and movable with its operating means for releasing an escapement mechanism after said stop has reached the limit of its travel and disposed to be operated by a single finger simultaneously with the operation of a column-stop, and means for permitting a continued movement of the stop-operating means subsequently to the completion of the travel of a denomination-stop.

27. In a tabulator for type-writers, the combination with a suitable stop means and a series of keys for actuating the same, to stop the carriage in proper position for the arrangement of a column of figures, means to permit a continued movement of the stop-keys after the stop has reached the limit of its travel into operative position, of a release-key perforated for the free passage of the tabulator-keys and movable therewith, connection from said release-key to the carriage-feed mechanism whereby the carriage may be released to permit it to move into contact with the stop after it has reached the limit of its travel, as specified.

28. In a tabulator for type-writers, the combination with a suitable stop means and a series of keys for actuating the same to stop the carriage in proper position for the arrangement of a column of figures, means to permit a continued movement of the stop-keys after the stop has reached the limit of its travel into operative position, of a transverse release-bar perforated for the free passage of the tabulator-keys and movable therewith; connections from said bar to the carriage-feed mechanism whereby the carriage may be released to permit it to move into contact with the stop after it has reached the limit of its travel, as specified.

In testimony whereof I affix my signature in presence of two witnesses.

WALTER JESSE SPIRO.
